US0D1029956S

(12) **United States Design Patent** (10) **Patent No.:** **US D1,029,956 S**
(45) **Date of Patent:** **** Jun. 4, 2024**

(54) **TOY SCREWDRIVER**

(71) Applicant: **Xusheng Weng**, Guangdong (CN)

(72) Inventor: **Xusheng Weng**, Guangdong (CN)

(**) Term: **15 Years**

(21) Appl. No.: **29/823,994**

(22) Filed: **Jan. 21, 2022**

(51) LOC (14) Cl. **21-01**

(52) U.S. Cl.

USPC **D21/532**

(58) **Field of Classification Search**

USPC D21/532, 579, 615, 708; D8/82, 83
CPC A63F 11/0025; A63F 2001/003; B25B

15/00; B25B 17/00

(57) **CLAIM**

The ornamental design for a toy screwdriver, as shown and described.

DESCRIPTION

FIG. 1 is a perspective view of the toy screwdriver showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show portions of the toy screwdriver that form no part of the claimed design.

1 Claim, 8 Drawing Sheets
